UNITED STATES PATENT OFFICE.

BERRY COPELAND AND JACOB W. GIRTON, OF SHELBYVILLE, INDIANA.

ROAD DRAG.

Application filed July 24, 1923. Serial No. 653,502.

To all whom it may concern:

Be it known that we, BERRY COPELAND and JACOB W. GIRTON, citizens of the United States, residing at Shelbyville, in the county 5 of Shelby and State of Indiana, have invented new and useful Improvements in Road Drags, of which the following is a specification.

This invention relates to road building 10 machinery and more particularly to road drags.

The primary object of this invention resides in the provision of a road drag adapted to fill and level vehicle tracks worn in roads 15 and distribute any surplus road material, remaining from the filling and leveling operation, across the surface of the road.

Another object of this invention resides in the provision of a road drag adapted to 20 initially fill and level vehicle tracks worn in a road and finally distribute any surplus road material, remaining from the filling and leveling operation, across the road surface so minor depressions will be filled and 25 leveled and all large rocks or the like cast aside.

With these and other objects in view, this invention resides in certain novel features of construction, arrangement and combination 30 of elements to be hereinafter set forth in the specification, illustrated in the accompanying drawings and pointed out in the appended claims.

In the accompanying drawings:

35 Fig. 1 is a side view of a road drag constructed in accordance with this invention.

Fig. 2 is a plan view thereof with the truck removed.

Fig. 3 is a bottom plan view.

40 Fig. 4 is a front view thereof.

Fig. 5 is a cross-sectional view on line 5-5 of Fig. 2.

Fig. 6 is a similar view on line 6-6 of Fig. 2.

45 In the present embodiment of this invention the numeral 5 designates a truck which consists of a frame 6 preferably supported at its rear end by two wheels 7 and at its front end by a single wheel 8.

50 Carried beneath the truck 5 as by means of links 9 or the like is a drag frame 10 to the under side of which is secured scraper blades 11, a leveling blade 12 and a distributing blade 13.

55 The aforesaid scraper blades 11 are lo-

cated at the front end of the frame 10 and are arranged so as to converge rearwardly and provide a passageway 14 adjacent what would be their point of intersection to permit the loose road material collected by the 60 blades to be discharged in the vehicle tracks formed in the road over which the drag is drawn. In forming the passageway 14, the rear end of one of the blades 11 terminates somewhat forward of that of the other so as to discharge the road material in the path of the leveling blade 12.

The aforesaid leveling blade 12 is disposed diagonally to the rear of the scraper blades 11 and is provided with a passageway 70 15 lying out of alignment with the passageway 14 so the road material deposited in the vehicle tracks, in alignment with the passageway, will be leveled and any surplus material remaining from the leveling operation 75 will be directed through the passageway 15 for further distribution by the distributing blade 13.

The distributing blade 13 is located to the 80 rear of the leveling blade 12 and extends diagonally across the frame in the opposite direction occupied by said leveling blade 12 so the road material discharged through the passageway 15 will be distributed across the road surface to fill minor depressions. 85

With the ground engaging blades arranged as aforesaid, that area of the road subjected to the greatest wear will initially be filled and leveled, after which the surplus road material will be distributed across the road, and any large rocks or the like in the path of the blades will be cast to one side of the road out of the path of vehicles. 90

In the present disclosure the drag frame is 95 constructed of wooden beams having its ground engaging blades protected by metal but, where the drag is made entirely of metal, the blades will be formed to provide passageways such as 14 and 15.

With this invention fully set forth, it is 100 manifest that a road drag of great utility is produced and, through the particular arrangement of the ground engaging blades, that area of a road subjected to the greatest wear can readily be repaired in the minimum length of time.

Having thus described our invention, what we claim and desire to protect by letters patent is:

1. A road drag of the character set forth 110

comprising a drag frame, scraper blades carried thereby, a leveling blade to the rear of the scraper blades and having its lower edge disposed on different horizontal planes with 5 a passageway dividing the lowermost edge of the leveling blade disposing the uppermost edge on one side thereof and the lowermost edge on the other side thereof, and a distributing blade to the rear of the leveling 10 blade.

2. A road drag of the character set forth comprising a frame, scraper blades carried thereby, a leveling blade to the rear of the scraper blade and having its ground engaging edge cut away from one side thereof and continued into a passageway of greater 15 height than the cut away portion, and a dis-

tributing blade to the rear of the leveling blade.

3. A road drag of the character set forth 20 comprising a frame, scraper blades carried at the forward end thereof, a leveling blade disposed to the rear of the scraper blades and having the major portion of its ground engaging edge lying on a horizontal plane 25 beneath the plane occupied by the minor portion thereof with an enlarged passageway separating the major portion and minor portion thereof, and a distributing blade to the rear of the leveling blade. 30

In testimony whereof we affix our signatures.

BERRY COPELAND.
JACOB W. GIRTON.
